away, taken substantially along line 8-8 of Fig. 2;

Fig. 9 is a vertical section taken through the longitudinal center line of the igniter body;

Fig. 10 is a vertical section taken substantially along line 10-10 of Fig. 9;

Fig. 11 is a partial vertical section similar to Fig. 10 but showing a modified form of air valve for the igniter;

Fig. 12 is a partial section similar to Fig. 9, showing the igniter body provided with a plurality of secondary air admission openings;

Fig. 13 is a view corresponding to Fig. 12, showing a modification of the igniter body; and

Fig. 14 is a schematic wiring diagram of an automatic control circuit incorporated in the form of the invention illustrated in Fig. 2.

Referring to Fig. 1, there is shown in dash outline a portion of the outer casing of an oil burning appliance which is provided with an access door opening. An oil burner 10 comprising an open receptacle having a cylindrical side wall is mounted in the casing, preferably upon legs 11 whereby the bottom of the burner is raised above the floor level of the appliance so as to permit the flow of cooling air beneath the burner to protect the floor from over heating. In accordance with usual practice, the vertical wall of the burner is provided with a plurality of air inlets 12, the same being arranged in a plurality of vertically spaced rows, the lowermost row being sufficiently above the bottom of the burner that oil cannot flow therethrough even though the fire should be extinguished and the oil should continue to flow. In accordance with my invention, an oil inlet 13 is provided in the side wall of the burner relatively close to the bottom thereof, the opening being about three-fourths of an inch in diameter. An internally threaded nipple 14 is welded to the wall concentrically about the oil inlet 13. The opening 13 may be an enlargement of the opening ordinarily provided for attachment of the oil inlet pipe, or the regular oil inlet pipe may be capped or plugged and a separate opening provided, either operation being readily achieved in the field by the use of ordinary tools without necessarily removing the burner from the appliance. Of course, it is to be appreciated that when the igniter is being assembled with a burner in the factory where the appliance and burner are assembled, the opening 13 would be the only opening required since it constitutes the oil inlet for the burner. When the nipple 14 is attached to the burner, as illustrated in Fig. 1, the burner is ready for association therewith of the igniter of the present invention.

The preferred form of the igniter comprises a cast fitting, made of brass or other suitable alloy, the same preferably comprising an elongated, hollow body 20 resembling a short section of cast pipe. The inner end of the body is externally cylindrical and provided with standard pipe threads 21 adapted to be threadedly engaged with the internal threads of the nipple 14. When the igniter is being attached to the burner the fitting is screwed into the nipple until a tight fit is obtained when an extension 22 of the fitting extends vertically above the body 20. The extension 22 is in the form of a hollow riser or wall having a rectangular cross-section, and its upper edge is located above the highest level to which oil may flow from the usual float valve or equivalent. The front and rear walls of the extension are preferably provided with ribs 23 on the outer surface thereof, in the upper ends of which screw

receiving openings 24 are provided. The upper portion of one side wall is provided with a large air inlet opening 25 which is located at a little distance below the upper end edge of the extension, but still above the highest oil level. The base of the opposite wall of the extension is provided with an internally threaded boss 26 to which the oil inlet tube 27 may be connected as through the means of an elbow 28. The base of the front wall of the extension is provided with an internally threaded boss 29 in which is seated a threaded clean-out plug 30, the plug being in alignment with the axis of the body 20 so that a cleaner rod may be utilized to remove any carbon deposit which may form on the floor of the burner in front of the outlet of the body 20. The external surface of the boss 29 is preferably formed with flat sides so that the fitting may be engaged by a wrench. The base of the wall in which opening 25 is provided is threaded for the reception of a pair of screws 31 which attach the lower end of a bimetallic strip 32 to the fitting. The upper end of strip 32 carries a valve body, the stem portion thereof being indicated at 33. The valve body is more fully illustrated in Fig. 10 or 11, the preferred form being indicated at 34 in Fig. 10. Adjoining the inner wall of the extension 22 and extending toward the threads 21 there is preferably provided an upwardly extending ridge 35 of sufficient height to extend above the highest level to which oil may flow from the usual control means. One or more small air inlet openings 36 may be drilled vertically downward through the ridge 35 into the interior of the body 20.

The upper end of the extension 22 is closed by a refractory, dielectric plug 40, details of which may be more clearly ascertained from inspection of Figs. 9 and 10. The plug is molded around the ends of a pair of insulated conductors 41 which extend through the plug and the inner ends of which are joined by a short length of resistance wire forming a resistance element 42 shaped into the form of a bail, the ends of the conductors 41 and of the resistance element 42 being preferably abutted and fused together. The plug 40 is preferably formed of material which may be melted at high temperatures and poured into place around the wires 41 while they are being retained in proper relation to a receptacle 43 having a pair of openings through the bottom thereof through which the wires extend and about which the material of the plug may flow to insulate the wires from the receptacle. The receptacle is preferably provided with a horizontal flange extending about its upper edge, which flange is adapted to overlie the upper edge of the extension 22 to provide means for fastening the plug in position, this being accomplished by a pair of screws 45 threaded into the openings 24 with their heads overlying and gripping the flange of the receptacle 43. The resistance element 42 pivotally supports a block wick 46 of porous, capillary material which may be of ceramic, refractory substance, but is preferably formed of sintered, powdered metals of high resistance to heat and corrosion such as various alloys of brass or nickel. The plug is formed with a transverse opening 47 of substantially larger diameter than the diameter of the resistance element 42. The resistance element 42 comprises a relatively rigid wire of relatively large diameter formed of an alloy of nickel or the like having a high resistance to corrosion and heat and which will retain its shape when heated or when subjected to rough

handling. The block wick 46 comprises a wick capable of rapidly soaking up oil through the pores thereof by capillary action, and the lower end thereof extends almost to the lower, inner surface of the fitting in line with the interior of the boss 26 through which the oil enters. The conductors 41 are preferably insulated by material resistant to the attack of oil or corrosive substances contained in the oil or resulting from combustion thereof and resistant to deterioration under heat. They are preferably of short length so that if replacement is necessary no great expense is involved. The outer ends of the conductors are bent downwardly and are inserted into vertical contact openings 50 in a transformer 51 preferably mounted inside of the appliance casing as by means of a plurality of mounting studs 52. The transformer is supplied with current through a pair of conductors 53 protected by a flexible, metallic conduit 54, and the transformer is controlled by a manual switch including a button 55 which may be mounted on a portion of the casing and which is connected to the transformer through a pair of insulated conductors 56. The switch is of the normally open type and current will flow through the resistance element 42 only as long as the button 55 is depressed.

In the form of the invention illustrated in Fig. 1 it is to be appreciated that the tube 27 is connected to some form of manually controlled oil regulating valve (not shown) which is opened to the desired extent when the appliance is to be fired. Oil flowing into the body 20 contacts the wick 46 and a portion thereof is diverted through the capillarities thereof so that within a few seconds after depression of the switch button 55 a pilot flame will commence to burn about the upper portion of the wick 46 due to vaporization and ignition of some of the diverted oil by the resistance element 42. Air to support combustion enters through the air inlet 25, the bimetallic strip 32 being so arranged as normally to hold the valve 34 away from its seat. The opening 47 provides means to permit access of air to the oil which is being volatilized by the resistance element so that the first ignition of oil takes place at the ends of the opening 47, the interior thereof being highly heated and providing a small carbureting chamber. The flame soon spreads over the entire surface of the plug 46 and sweeps through the interior of the body 20 along with the oil flowing therethrough. The interior of the body 20 forms an oil conduit or passage which is of such height throughout that an open, flame conducting passage extends to the interior of the burner above the oil flowing therethrough at all times. The oil entering the burner and spreading out over the bottom thereof is thus ignited and commences to heat the burner to such an extent that vaporization of fuel will continue. In the preferred form of the apparatus ignition of the oil at the region of the wick 46 occurs in ten to fifteen seconds after the button 55 is depressed, and experience will teach the operator the length of time it is necessary to hold the button depressed, whereupon it may be released and the operation will continue without manual attendance. The flame in the interior of the extension 22 soon heats the walls thereof to such an extent that the bimetallic strip is warped toward the extension, thus seating the valve body in the opening 25 and preventing further ingress of combustion-supporting air. The flame within the interior of the igniter is

thus snuffed out, this action preferably occurring within approximately one minute after ignition occurs. The openings 36 are provided to permit a continuous supply of vapor purging air to flow through the body 20 and, secondly, to supply secondary air to support the flame along the interior of body 20. The number, diameters and arrangement of the openings 36 may vary, the best results being experimentally determined for each burner or appliance so that combustion-supporting air and purging of the fitting will occur without upsetting the balance of the burner. As soon as the pilot flame around the wick 46 has been snuffed out the bimetallic strip 32 will commence to cool and warp outwardly to open the air inlet opening 25 so that thereafter a large volume of air will purge the igniter and prevent backflow of flame thereinto. The length of the body 20 is preferably such as to space the bimetallic strip 32 sufficiently from the burner to prevent heat radiating from the burner from closing the air inlet opening 25.

As seen in Fig. 1, two secondary air inlet openings 36 are provided, while in Fig. 9 the ridge 35 is provided with only one such opening; in Fig. 12 the ridge 35 has been provided with three openings 36, illustrative of one experimentally determined variation thereof; and in Fig. 13 the body 20 is illustrated as being cast without the ridge 35 for use in connection with a combination of burner and appliance in which it has been experimentally determined that the secondary air inlet openings 36 are unnecessary. A detail illustrated in Fig. 10 is with respect to the valve body 34 and the air inlet opening 25. It will be observed that the valve body has a rounded inner surface and the stem thereof is loosely positioned in an enlarged opening through the bimetallic strip 32. The valve body therefore may shift about or cant to a limited extent. Preferably the outer end of the air inlet opening 25 is surrounded by a countersink 57 providing a sharp edge at the outer end of the opening 25 against which the valve body 34 may be firmly seated. In the modification disclosed in Fig. 11, the outer end of the air inlet opening 25 is provided with a conical countersink 58 in which a conical valve body 59 may be seated. It will be appreciated that other forms and arrangements of valve and valve seat may be provided within the scope of my invention.

In the form of the invention illustrated in Figs. 2 to 8 inclusive, the igniter previously described has been associated with a pressure-fired oil burner which is automatically controlled. The burner 10 is surrounded by a pressure chamber 60, the upper end of which is attached to the heat exchanger 61 in the usual manner. An opening 62 is provided in the wall of the pressure chamber 60, and a fixed portion of a housing is mounted on the wall of the chamber surrounding said opening. The fixed portion of the housing includes a bottom wall 63, a side wall 64, an opposite side wall 65, and a top wall 66. A plurality of the walls are provided with clip bars such as 67 and 68 mounted on the outer and inner surfaces, respectively, of the forward edges thereof, for reception of the walls of a removable housing portion including a bottom wall 70 complementary to the wall 63, a side wall 71 complementary to the side wall 64, an opposite side wall 72 complementary to the side wall 65, a top wall 73 complementary to the top wall 66, and an end wall 75. The bottom wall 70 has an opening there-

through which is positioned an air propeller 76 mounted on the vertical shaft 77 of a motor 78 supported by a plurality of legs 79 fastened to the bottom wall 70. When the motor is in operation air is forced into the housing, through the opening 62 into the pressure chamber 60, and into the burner 10 through the openings 12. In order that the air may be evenly distributed throughout the interior of the housing, a baffle plate 80 is mounted above the impeller 76 upon a plurality of short legs 81, the baffle plate extending beneath the outer end of the igniter body 20. It is obvious that air under pressure may enter the air inlet opening 25 when the bimetallic strip 32 is warped outwardly, and may constantly enter the secondary air inlets 36 in the ridge 35. Oil reaches the igniter fitting through an inlet pipe 82 which extends through the side wall 65. When it is desired to remove the fitting 20, the pipe 82 is disconnected, the outer portion of the housing removed, thus carrying with it the baffle 80 and the motor 78, the screws 45 are removed to permit the insulator plug 46 to be lifted from the extension 22, and the fitting may now be rotated by engagement of a wrench with the hexagonal portion 29. It is to be observed that the conductors 41 extend through notches provided in the engaging edges of the upper wall portions 66 and 73 so that the conductors and associated elements may be replaced with ease. A shield 83 may be mounted on wall 64 to protect the bimetallic strip 32 from the heat of the burner, preferably by bolts 84 which may be easily removed to permit rotation of the igniter body.

The oil inlet tube 82 extends into the bottom of a control valve support 85 and is attached to a control valve body 86 mounted in support 85. Oil is admitted to the control valve body 86 through an oil supply tube 87 which is in communication with the supply tank. It will be appreciated that flow through the tube 82 into the burner will be under control of the usual needle valve or metering valve (not shown) mounted in the valve body 86. Such devices are so common in the art that details thereof need not be illustrated. Mounted on top of the valve body 86 is a control box 90 including a removable portion 91 preferably provided with louvers to permit the circulation of cooling air therethrough. The portion 91 comprises a front wall and a top wall which are retained upon a fixed portion 92 including a back wall, a bottom wall and end walls, the removable portion being retained such as by means of spring clips 93. Current is supplied to controls mounted in the control box 90 through a cable 95 extending to a junction box 96 mounted upon the support 85. A second cable 97 leads from the junction box to the transformer 51 which is mounted on the back of the support 85 and from which the conductors 41 extend into the igniter. Current from the main line is led to the junction box 96 through the usual supply line (not shown) having a manual cut-off switch therein (not shown). The blower motor 78 is connected to control means in the control box 90 through a cable 98. The controls in the control box are also connected through a cable 99 to a safety switch indicated generally at 100 in Fig. 5, details of which are illustrated in Fig. 5, and through a cable 101 to a limit switch (not shown) in the appliance.

The safety switch 100 illustrated in Fig. 5 comprises a pair of spaced legs 105 and 106 which extend through an opening 107 in the bottom of

the pressure chamber 60, the lower extremities of the legs forming the end walls of a small housing 108 which completely encloses the opening 107. At least one leg, herein illustrated as leg 106, is bent laterally to provide an attaching flange through which a screw 109 passes into the bottom of the burner 10, a bimetallic strip 110 being held against the bottom of the burner by the screw 109. The outer end of the strip 110 is provided with a strap 111 to provide means pivotally to support the cross-piece of a curved, U-shaped member 112, the legs of which extend through openings 113 in the lower wall of the housing 108. A cross-piece 114 joins the extremities of the legs and supports an insulator screw 115 in contact with a spring actuator 116 of a snap switch including a switch bar 117. The switch bar carries a pair of insulated contacts, the upper of which is adapted to engage an insulated contact on the base plate 118 of the snap switch assembly, and the lower contact is adapted to engage an insulated contact mounted on an insulated arm 119 extending between the legs of the member 112. When the burner is cool the bimetallic strip is in the position illustrated in Fig. 5; thus the upper pair of contacts are in engagement with each other and constitute a normally closed pair of contacts. When the bottom of the burner is excessively heated the bimetallic element is warped upwardly, thus causing the switch bar 117 to snap downwardly to engage the normally open pair of contacts.

In Fig. 14 I have illustrated a schematic wiring diagram for use in combination with the assembly illustrated in Figs. 2 to 8 inclusive. In this diagram current is supplied through main lines 120 and 121 across which is positioned the primary winding of a transformer 122 mounted in the control box 90, the main lines being under control of the usual cut-out switch. When the main lines are supplied with current the primary of transformer 122 is energized. The secondary of transformer 122 is connected at one end through a wire 123 to a room thermostat 124 which, of course, may be supplemented by a manual switch 151 in the usual manner. The thermostat 124 is in series with a limit switch 125 which is so arranged as to be normally closed, but which may open to cause the fire to be extinguished if the bonnet temperature of a furnace, or the temperature of some portion of any appliance in which it is mounted, should become excessive. The limit switch is in series with a first resistance element 126 which is connected to the normally closed contact of the safety switch 100, the common switch bar thereof being indicated by the thermostatic element 110. Element 110 is connected by branch wire 127 and wire 128 to the opposite side of the secondary of transformer 122. Therefore, when the limit switch and the safety switch are cool and in their normal positions, as illustrated in Fig. 14, closing of the thermostat 124 will heat the element 126. Element 126 heats a bimetallic valve actuator 130 which warps to open the valve 150, causing oil to flow into the burner, and it simultaneously heats a bimetallic element 131 which warps to contact the end of a branch 132 of a wire 133 leading to the main line 120. The element 131 is connected by wire 135 to the primary winding of transformer 51 which is normally connected through wire 136 to a bimetallic element 140 having a wire 141 leading therefrom to the blower motor 78, the opposite side of which is connected by wire 142 to the opposite main line 121. There-

fore, as soon as bimetallic element 131 is heated sufficiently, a circuit will be completed to energize the secondary of transformer 51 and heat the igniter resistance element 42, and simultaneously cause operation of the blower motor 78 to force air through the opening 25 in the igniter and the air inlets 12 of the burner.

The blower motor should remain energized as long as the burner is under operation, but the igniter resistance element 42 should be de-energized as soon as it has accomplished its function. Therefore, means are provided to break the circuit through the element 42 and to re-establish a circuit through the blower motor 78 so that it will continue operating as long as the thermostat 124 is closed. In order to do this, a spaced pair of normally open contacts are provided above the bimetallic element 130. One of the contacts is at the end of a wire 146 branching from the line leading from the first resistance element 126 to the contact in engagement with bimetallic element 110, and, therefore, is connected through wires 127 and 128 to one side of the transformer 122. The other contact is connected by a wire 147 leading to a second resistance element 145, the opposite end of which is connected by wire 148 leading to the opposite side of transformer 122. Therefore, when the bimetallic element 130 has been heated for a longer period than ordinarily is required for the igniter to operate, it completes the circuit through the second resistance element 145. This causes the bimetallic element 140 to rise and make contact at its upper position, thus completing a circuit across the fan motor independently of the igniter and breaking the circuit to the igniter heater element. The blower will thus continue operating as long as the thermostat 124 is closed and the burner temperature is below a certain low limit. The resistance elements 126 and 145 and the bimetallic elements 130, 131 and 140 are of such character and so arranged with respect to each other that the element 131 makes contact a short interval of time after the oil valve opens, and the element 140 breaks from its lower contact and rises to its upper contact a short interval of time thereafter. It is generally preferable that the oil be permitted to flow for about one minute, so as to be certain that oil has reached the igniter and the floor of the burner, before the igniter is energized, and that the igniter remain energized for about ten to twenty seconds, a sufficient length of time for the igniter resistance element 42 to produce and ignite vapor from the oil soaked up into the wick.

As soon as the burner temperature exceeds the predetermined low limit the bimetallic element 110 of the safety switch 100 will move sufficiently to snap the contact bar 117 over to the opposite contact, thus completing a circuit through wires 128 and 127, the resistance element 145, and wire 148 back to the secondary of transformer 122. The element 145 therefore remains heated to keep the bimetallic element 140 at its upper position, completing an independent holding circuit through the blower motor 78 and preventing completion of the circuit through the igniter resistance element 42. The first resistance element 126 remains heated in spite of the movement of the bimetallic element 110, since the bimetallic element 130 has completed a circuit therethrough from thermostat 124 to the element 126, wire 146, bimetallic element 130 and wire 128 to the secondary of transformer 122.

If the thermostat 124 should now open, the bimetallic element 130 will cool and open the gap

between wires 146 and 147. However, the resistance element 145 will remain heated until the temperature of the burner causes the contact bar 117 to snap to its normal position as shown in Fig. 5. When that happens, the resistance element 145 will become cool, permitting bimetallic element 140 to move down to its normal position as illustrated in Fig. 14. Prior to this event, and at the same time that bimetallic element 130 is moving to its open position, the bimetallic element 131 has cooled and moved to its open position so that both the igniter resistance element 42 and the blower motor 78 are in open circuits ready for initiation of the next operation. It will be apparent that, from the time oil flow ceases until the burner bottom is cooled to a safe temperature, reignition is prevented. Also, since the bimetallic element 110 is in the opposite position from that illustrated in Fig. 14, the circuit through the first resistance element 126 is held open so that the oil valve cannot be reopened until the burner temperature is cool enough to permit oil to be admitted to the burner without danger.

Having illustrated and described preferred embodiments of my invention, it should be apparent to those skilled in the art that the invention permits of modification in arrangement and detail. I claim as my invention all such modifications as come within the true spirit and scope of the appended claims.

I claim:

1. An igniter for association with an oil burner of the type comprising an open receptacle in which oil is vaporized by the heat of combustion of previously formed oil vapor and mixed with air to form a combustible mixture, said igniter comprising a horizontally elongated, hollow member adapted to be attached to the burner in communication with the interior thereof to provide an oil inlet, said member comprising means to connect an oil feed line thereto adjacent its outer end and an open-topped, hollow extension rising from adjacent its outer end and communicating with the interior thereof, said extension having an auxiliary opening thereinto adjacent its upper end, an insulator closing the upper end of said extension, a pair of conductors extending through said insulator, a resistance element joining the inner ends of said conductors, a wick extending from said resistance element into the path of oil flowing into said member, a bimetallic strip mounted on said hollow member at one end and extending toward said auxiliary opening, and a valve mounted on the free end of said bimetallic strip, said bimetallic strip being arranged to hold said valve away from said auxiliary opening when cool and to move said valve toward said auxiliary opening when heated, and said valve being arranged to close said opening when said bimetallic strip is heated to a sufficient extent.

2. The construction set forth in claim 1 in which said member is provided with at least one permanently open, small hole in the upper surface thereof between said extension and the open end of the member.

3. The construction set forth in claim 1 in which said member comprises a ridge extending above the upper surface thereof between said extension and the open end of the member, and at least one permanently open, small hole extends downwardly through said ridge to the interior of said member.

4. The construction set forth in claim 1 in which the open inner end of said member is cylind-

circular and threaded for connection thereof to an oil burner having a threaded coupling member thereon.

5. The construction set forth in claim 1 in which said feed line is connected to said member at one side of the outer end thereof, the outer end of said member is provided with a threaded opening in alignment with the longitudinal axis thereof, and said member comprises a removable plug seated in said threaded opening.

6. The construction set forth in claim 1 in which said member is of such length as to space said bimetallic strip sufficiently from the burner that the heat radiating from the burner will not warp the bimetallic strip sufficiently to seat said valve member in said opening.

7. The construction set forth in claim 1 in which said valve member comprises a stem loosely mounted in the end of said bimetallic strip so as to permit angular shifting of said valve member whereby it may be seated firmly in said opening.

8. The construction set forth in claim 1 in which said bimetallic strip overlies the outer surface of said extension adjacent said wick.

9. The construction set forth in claim 1; in combination with means shielding said bimetallic strip from the heat of the burner.

10. The construction set forth in claim 1; in combination with a housing surrounding said extension, a casing forming a pressure chamber surrounding the burner and communicating with said housing, said housing having an inlet opening thereto, and a blower arranged to force air through said inlet opening, about said extension, and into said housing.

11. An igniter for association with an oil burner of the type comprising an open receptacle in which oil is vaporized by the heat of combustion of previously formed oil vapor and mixed with air to form a combustible mixture, comprising a horizontally elongated, tubular member adapted to be attached to the burner in communication with the interior thereof to provide an oil inlet, said member comprising means to connect an oil feed line thereto adjacent its outer end and an extension rising from adjacent the feed line connecting means, said extension being hollow and in communication with the interior of said member, electric igniting means arranged in said extension, said igniting means including a resistance element and a wick adjacent thereto with said wick extending into the path of oil flowing into said member, said extension having an air inlet opening adjacent said igniting means, a valve adapted to close said air inlet opening, and heat-responsive means adjacent said wick and arranged to move said valve to close said air inlet opening upon being heated.

12. An oil burner of the type comprising an open receptacle in which oil is vaporized by the heat of combustion of previously formed oil vapor and mixed with air to form a combustible mixture, said receptacle having an oil inlet opening of such size as to provide a pilot flame opening above the normal level of oil admitted therethrough, a combined oil inlet fitting and igniter mounted on said receptacle and comprising a hollow body including means to form a restricted passage leading to the receptacle, the interior of said body being of sufficient height above the normal oil level as to provide a continuation of said pilot flame opening, said body having a hollow extension rising therefrom in communication with the interior thereof, an electric ignition de-

vice comprising a resistance element mounted in said extension above the normal oil level and an adjacent wick extending to a point below the normal oil level in said body, said body and hollow extension thereof shielding said electric ignition device from the combustion area of said receptacle, said body comprising means to connect an oil feed line thereto whereby oil flowing into said receptacle through said body passes in proximity to said ignition device, said body having an air inlet opening above the normal oil level adjacent said ignition device whereby a pilot flame may be created in said body upon energization of said electric igniting means, and means to close said air inlet opening to snuff out said pilot flame.

13. A combined oil inlet and igniter for an oil burner of the type comprising an open receptacle in which oil is vaporized by the heat of combustion of previously formed oil vapor and mixed with air to form a combustible mixture, comprising a hollow metallic body adapted to be fixed to the oil burner receptacle in restricted communication with the interior thereof and near the bottom thereof to provide an oil inlet, a hollow riser on said body, an electric igniting means comprising a resistance element arranged in said hollow riser and an adjacent wick extending to a point below the normal oil level in said body, said hollow metallic body and hollow riser thereon shielding said electric igniting means from the combustion area of said receptacle, and means to admit oil into said body, said riser being arranged to receive oil in the bottom thereof, said body having an air inlet opening therein in such position as to admit air to support combustion of the oil ignited by said electric igniting means and cause the projection of a pilot flame into said receptacle, and means to close said air inlet opening whereby to extinguish the pilot flame.

14. A combined oil inlet and igniter for a vaporizing oil burner of the type comprising an open receptacle having an interior portion onto which oil may flow to be evaporated by the heat of combustion, said receptacle also comprising air inlet means for continuously admitting air to mix with the evaporated oil and support combustion thereof, comprising a member adapted to be mounted on and extend outwardly from the burner, said member comprising means for connecting an oil inlet conduit thereto and a portion forming a substantially horizontal passage through which oil may flow from said oil inlet conduit onto said interior portion, said passage being of such height throughout that a substantial portion thereof remains open to the interior of the receptacle above the oil flowing therethrough, means forming a closed chamber rising above said passage and communicating therewith, said chamber having an air inlet opening thereinto at a level above said passage, an electric igniter mounted in said chamber and adapted to set fire to the oil flowing through said passage whereby combustion in the receptacle may be initiated by flame spreading into the interior of the receptacle through said passage, said igniter comprising a resistance element and an adjacent wick extending into proximity with the bottom of said passage, and heat responsive means associated with said member and movable to close said air inlet opening a short while after ignition of fuel by said igniter.

15. A combined oil inlet and igniter for a vaporizing oil burner of the type comprising an open receptacle having an interior evaporating

surface onto which oil may flow to be evaporated by the heat of combustion, said receptacle also comprising air inlet means for continuously admitting air to mix with the evaporated oil and support combustion thereof, comprising a fixture adapted to be mounted on and extend outwardly from the burner, said fixture comprising means for connecting an oil inlet conduit thereto and a portion forming a substantially horizontal passage through which oil may flow from said oil inlet conduit onto said evaporating surface, said passage being of such height throughout that a substantial portion thereof remains open to the interior of the receptacle above the oil flowing therethrough, said fixture also comprising means forming an open well rising above said passage and communicating therewith, said well having an air inlet opening thereinto at a level above said passage, means closing said well to form a closed chamber therewith, an igniter including electric resistance means and an adjacent wick mounted in said chamber and adapted to set fire to the oil flowing through said passage whereby combustion in the receptacle may be initiated by flame spreading into the interior of the receptacle through said passage, and valve means adapted to close said air inlet opening at an interval after the oil in said passage is ignited.

16. A combined oil inlet and igniter for a vaporizing oil burner of the type comprising an open receptacle having an interior evaporating surface onto which oil may flow to be evaporated by the heat of combustion, said receptacle also comprising a wall having a plurality of perforations therethrough for continuously admitting air to mix with the evaporated oil and support combustion thereof, comprising a fixture adapted to be mounted on and extend outwardly from the burner, said fixture comprising means for connecting an oil inlet conduit thereto and a portion forming a substantially horizontal passage through which oil may flow from said oil inlet conduit onto said evaporating surface, said passage being of such height throughout that a substantial portion thereof remains open to the interior of the receptacle above the oil flowing therethrough, said fixture also comprising means forming an open well rising above said passage and communicating therewith, said well having an air inlet opening thereinto at a level above said passage, means closing said well to form a chamber therewith, an electric igniter including electric resistance means mounted in said chamber and wick means adjacent said electric resistance means and extending to the oil level in said passage whereby combustion may be initiated in said fixture and operation of the burner will result from flame spreading into the interior of the receptacle through said passage, and valve means including a bimetallic actuator mounted on said well and susceptible to heat radiated therefrom and a valve movable by said actuator to close said air inlet opening at an interval after initiation of combustion in said passage whereby the flame in said passage is automatically snuffed out a short while after being kindled.

17. A combined oil inlet and igniter for a vaporizing oil burner of the type comprising an open receptacle into which oil may flow to be evaporated by the heat of combustion and air inlet means for continuously admitting air to mix with the evaporated oil and support combustion thereof, comprising a fixture adapted to be mounted on and extend outwardly from the burner, said fixture comprising means for connecting an oil

inlet conduit thereto and a portion forming a substantially horizontal passage through which oil may flow from said oil inlet conduit into said receptacle, said passage being of such height throughout that a substantial portion thereof remains open to the interior of the receptacle above the oil flowing therethrough, said fixture also comprising means forming an upwardly opening well rising above said passage and communicating therewith, said well having an air inlet opening thereinto at a level above said passage, means closing the top of said well, an electric igniter including electric resistance means and an adjacent wick mounted in said well and adapted to set fire to the oil flowing through said passage whereby combustion in the receptacle may be initiated by flame spreading into the interior of the receptacle through said passage, valve means including a heat-responsive member mounted on said well and susceptible to heat radiated therefrom to close said air inlet opening at an interval after initiation of combustion in said passage whereby the flame in said passage is automatically snuffed out a short while after being kindled, and means shielding said heat-responsive member against radiation from said receptacle whereby said valve means reopens to permit air to flow through said passage after the flame therein is snuffed out in order that said passage may be kept free of combustion products during operation of the burner.

18. A combined oil inlet and igniter for a vaporizing oil burner of the type comprising an open receptacle having an interior portion onto which oil may flow to be evaporated by the heat of combustion, said receptacle also comprising air inlet means for continuously admitting air to mix with the evaporated oil and support combustion thereof, comprising a member adapted to be mounted on and extend outwardly from the burner, said member comprising means for connecting oil inlet means thereto and a portion forming an oil conduit through which oil may flow from said oil inlet means onto said interior portion of the receptacle, said member also comprising means forming a flame passage therethrough communicating with said oil conduit and with the interior of the burner receptacle adjacent said interior portion, said member having an air admitting opening for supplying air to said flame passage, means to divert a portion of the oil from said oil conduit into said flame passage, a resistance type electric heater mounted in said flame passage adjacent said diverting means for vaporizing some of the diverted oil and igniting the resulting mixture of oil vapor and air admitted through said air inlet opening, the resulting flame being directed toward said interior portion of the burner receptacle through said flame passage to initiate combustion in the burner receptacle, and means for closing said air admitting opening after ignition of the mixture of oil vapor and air in said flame passage has occurred in order to snuff out the flame in said flame passage.

19. A combined oil inlet and igniter for a vaporizing oil burner of the type comprising an open receptacle having an interior portion onto which oil may flow to be evaporated by the heat of combustion, said receptacle also comprising air inlet means for continuously admitting air to mix with the evaporated oil and support combustion thereof, comprising a member adapted to be mounted on and extend outwardly from the burner, said member comprising means for connecting oil inlet means thereto and a portion forming an oil conduit through which oil may flow from said oil

inlet means onto said interior portion of the receptacle, said member also comprising means forming a flame passage therethrough communicating with said oil conduit and with the interior of the burner receptacle adjacent said interior portion, said member having an air admitting opening for supplying air to said flame passage, means to divert a portion of the oil from said oil conduit into said flame passage, a resistance type electric heater mounted in said flame passage adjacent said diverting means for vaporizing some of the diverted oil and igniting the resulting mixture of oil vapor and air admitted through said air inlet opening, the resulting flame being directed toward said interior portion of the burner receptacle through said flame passage to initiate combustion in the burner receptacle, means for closing said air admitting opening after ignition of the mixture of oil vapor and air in said flame passage has occurred in order to snuff out the flame in said flame passage, and means effective to reopen said air admitting opening after the flame in said flame passage is extinguished whereby scouring air may pass through said flame

5

passage while normal combustion takes place within the burner receptacle.
